(57) **CLAIM**

The ornamental design for a handle for a tool, as shown and described.

DESCRIPTION

FIG. 1 is a perspective view of a handle for a tool according to the present design.

FIG. 2 is a front view of the handle for a tool of FIG. 1.

FIG. 3 is a rear view of the handle for a tool of FIG. 1.

FIG. 4 is a left side view of the handle for a tool of FIG. 1.

FIG. 5

is a right side view of the handle for a tool of FIG. 1.

FIG. 6 is a top side view of the handle for a tool of FIG. 1.

FIG. 7 is a bottom side view of the handle for a tool of FIG. 1.

FIG. 8 is an exploded view of the handle for a tool of FIG. 1; and,

FIG. 9 is an exemplary view of the use of the handle for a tool of FIG. 1.

The dashed dotted lines and dashed double dotted lines form no part of the claimed design.
